UNITED STATES PATENT OFFICE.

JACOB W. BAKER, OF DOVER, NEW JERSEY.

BRAKE-BEAM.

SPECIFICATION forming part of Letters Patent No. 438,462, dated October 14, 1890.

Application filed August 21, 1890. Serial No. 362,626. (No model.)

To all whom it may concern:

Be it known that I, JACOB W. BAKER, of Dover, in the county of Morris and State of New Jersey, have invented a new and useful 5 Improvement in Brake-Beams, of which the following is a full, clear, and exact description.

This invention relates to trussed brake-beams for railway-car use; and it consists in 10 a novel construction of the same, and in means connected therewith for holding and securing the spring which relieves or holds back the brake-shoe, substantially as hereinafter described, and more particularly pointed out 15 in the claims.

Reference is to be had to the accompanying drawings, forming a part of this specification, in which similar letters of reference indicate corresponding parts in all the figures.

20 Figure 1 represents a plan view of my improved brake-beam with pull-rod devices, hangers, brake-heads, shoes thereof, and brake-spring attached, showing the same applied to a pair of a railway car or truck wheels, 25 shown only in part. Fig. 2 is a front elevation of the same, in part, applied to a railway-car-truck body. Fig. 3 is a transverse vertical sectional view upon the line 3 3 in Fig. 2, looking in direction of the arrow therein. 30 Fig. 4 is a sectional view, in part, upon the line 4 4 in Fig. 2; and Fig. 5 is a sectional view upon the line 5 5 in Fig. 4, looking in direction of the arrow therein.

A indicates the trussed brake beam or bar, 35 which is composed of two flat wrought-metal bars *b c*, set edgewise uppermost, the outer or back one *c* being arched or bent to form, in connection with the other or front bar *b*, which is straight, and with the brace-piece *d* at the 40 arch or center of the trussed beam. These bars *b c* are not welded to each other at their ends, but are doubled over or bent at such parts, the bar *c* upon itself, as at *e*, and the bar *b* doubled over, as at *f*, to receive within it 45 the doubled-over ends of the bar *c*, after which bolts *g* are inserted to firmly clamp the doubled-over ends of the two bars together, which bolts may also be used to secure the brake blocks or heads *B*, holding the shoes 50 *C* to the brake-beam. This forms a very simple and strong construction of the brake-beam at

its ends and provides for its ready substitution for the ordinary wooden brake-beam to be used in connection with the standard brake-heads, as adopted by the Master Car Builders' Association of the United States. The trussed brake-beam *A* is further stiffened or supported at its center, and the brace or arch piece *d* united therewith by tubular stays *h h* and *i*, and bolts passing through said tubular 60 stays and through the bars *b c* of the brake-beam. Thus the tubes *h h* are arranged between the beam-bar *c* and side flanges on the arch-brace *d*, and the bolts *k k* passed through said tubes, the flanges on the arch-brace *d* 65 and the bars *b c*, while the center tube *i* is arranged between the bar *b* and the back of the arch-brace *d*, and the bolt *l*, which has the usual jaw-head *m* for connection therewith of the pull-rod mechanism *D D'* of the brake, 70 passes through said tube *i*, arch-brace *d*, and bars *b c* of the beam. All of these bolts *k k l* are of course adjustable to tighten up their hold.

E and F indicate the usual or any suitable 75 brake-hangers, and G is the spring which keeps the brake-shoes clear of the truck-wheels *H H* when the brake is not drawn or forced onto them. This spring, which is of approximately **C** form and adjustable, is secured at its top to the car-truck body *I*, as by bolts *n*, and is arranged below to lie on top of the brake-beam *A*, with its forward lower end bent down to lap over or against the front side of the bar *b* of the beam, and the bolt *l*, 80 85 which thus has a double function, passes through said bent end *s*, and clamps it by the jaw-head *m* tightly against the bar *b* of the beam. Said spring *G* is further secured at its base to the top of the brake-beam by a circular clip *v*, arranged around the tubular stay *i* next to the back of the arch brace-piece *d*, and provided with an integral screw-stud *w*, which passes through the spring and is tightened up by a nut on the outside. Thus the 95 spring *G* is firmly held to its position on the brake-beam both back and front.

Having thus fully described my invention, I claim as new and desire to secure by Letters Patent—

1. The trussed brake-beam, composed of an arched back bar doubled over upon itself at

its ends, a front bar having its ends doubled over the folded ends of the arched bar, and fastenings clamping the doubled ends of both bars together, substantially specified.

5 2. The combination of the arched back bar and front bar of the beam having their ends engaged with one another, as described, bolts uniting said independent bars at their ends, a center-arch brace-piece between the bars, 10 and tubular stays and bolts passing through said stays uniting the back and front bars of the beam and arch brace-piece together, essentially as described.

3. The combination, with the brake-beam, 15 of the spring G, arranged to lie on top of said beam and having its base constructed with a

bent lower extremity s, adapted to lie over or against the front of the brake-beam, and the bolt l, with its jaw-head m arranged to clamp said bent end of the spring to the beam, substantially as specified.

4. In combination with the brake-beam, and the spring G, having its base end constructed to lap over the front of the beam, the clip v, applied to said beam and provided with a stud w, arranged to pass through the rear portion of the spring and adapted to be secured on the inner side thereof, essentially as specified.

JACOB W. BAKER.
